US0D1021494S

(12) **United States Design Patent** (10) Patent No.: **US D1,021,494 S**
(45) Date of Patent: ** Apr. 9, 2024

(54) **PORTABLE PLATFORM**

(71) Applicant: **Quality Wood Designs, Inc.**, Mitchell, SD (US)

(72) Inventor: **Michael A. Honermann**, Mitchell, SD (US)

(73) Assignee: **Quality Wood Designs Inc.**, Mitchell, SD (US)

(**) Term: **15 Years**

(21) Appl. No.: **29/764,972**

(22) Filed: **Jan. 5, 2021**

(51) LOC (14) Cl. **06-03**

(52) U.S. Cl.

USPC **D6/384**; D6/349; D25/65

(58) **Field of Classification Search**

USPC D6/334, 349-353, 384, 684; D25/62, 63, D25/65

CPC A47C 12/00; A47C 16/02-04

CLAIM

The ornamental design for a portable platform, as shown and described.

DESCRIPTION

FIG. 1 is a perspective view of a first embodiment of my new design;

FIG. 2 is a left side view thereof;

FIG. 3 is a right side view thereof;

FIG. 4 is a front thereof;

FIG. 5 is a back view thereof;

FIG. 6 is a top view thereof;

FIG. 7 is a bottom view thereof;

FIG. 8 is a perspective view of a second embodiment thereof;

FIG. 9 is a left side view thereof;

FIG. 10 is a right side view thereof;

FIG. 11 is a front thereof;

FIG. 12 is a back view thereof;

FIG. 13 is a top view thereof;

FIG. 14 is a bottom view thereof;

FIG. 15 is a perspective view of a third embodiment thereof;

FIG. 16 is a left side view thereof;

FIG. 17 is a right side view thereof;

FIG. 18 is a front thereof;

FIG. 19 is a back view thereof;

FIG. 20 is a top view thereof;

FIG. 21 is a bottom view thereof;

FIG. 22 is a perspective view of a fourth embodiment thereof;

FIG. 23 is a left side view thereof;

FIG. 24 is a right side view thereof;

FIG. 25 is a front thereof;

FIG. 26 is a back view thereof;

FIG. 27 is a top view thereof; and,

FIG. 28 is a bottom view thereof.

The broken lines represent portions of the portable platform which form no part of the claimed design.
